UNITED STATES PATENT OFFICE.

JAMES C. COVERT, OF WATERVLIET, NEW YORK, ASSIGNEE TO THE COVERT MANUFACTURING COMPANY, OF SAME PLACE.

DESIGN FOR A GUARD FOR HOOKS.

SPECIFICATION forming part of Design No. 33,360, dated October 16, 1900.

Application filed September 20, 1900. Serial No. 30,629. Term of patent 14 years.

To all whom it may concern:

Be it known that I, JAMES C. COVERT, a citizen of the United States, residing at Watervliet, in the county of Albany and State of New York, have invented and produced a new and original Design for a Guard for Hooks; and I do hereby declare the following to be a full, clear, and exact description of the same, reference being had to the accompanying drawings, forming a part thereof.

This invention relates to a new and original design for a guard for hooks; and it is embodied in the structure having the form and configuration shown in the accompanying drawings.

In the drawings the design is shown in Figure 1 in perspective looking from the front, and in Fig. 2, a similar view looking from the rear.

Generally the design comprehends a guard having sides A, formed with curved lower edges and spaced apart, the upper edges being united by continuations and forming a substantially-straight surface. The rear portion of the sides A terminate in substantially a straight course, as at B, and the top portion or connection is extended back to the straight course or edge, so that the upper or

top portion represents an unbroken continuation from front to rear. Its extreme rear is slightly curved, as shown. The guard conveniently is formed in the shape of a U in cross-section and has, as represented, a straight forward edge. It is also provided with openings D at or near the rear portion, as shown.

While the particular design illustrated and described includes the invention, the essential features of the design may be stated as residing more particularly in the peculiar formation of the guard, having the unbroken connecting portion or top extending from front to rear and the rear edges terminating at the top.

Having thus described the invention, what is claimed as new, and desired to be secured by Letters Patent, is—

The design for a hook-guard, substantially as shown and described.

In testimony whereof I affix my signature in presence of two witnesses.

JAMES C. COVERT.
